UNITED STATES PATENT OFFICE.

WILLIAM A. MELIUS, OF GHENT, NEW YORK.

GAME APPARATUS.

1,176,076.

Specification of Letters Patent. Patented Mar. 21, 1916.

Application filed September 10, 1915. Serial No. 50,005.

To all whom it may concern:

Be it known that I, WILLIAM A. MELIUS, a citizen of the United States, residing at Ghent, in the county of Columbia and State 5 of New York, have invented new and useful Improvements in Game Apparatus, of which the following is a specification.

This invention relates to game apparatus and the principal object of the invention is to provide a game which may be played by one or more persons of any age 10 and which will be amusing and entertaining and which also affords puzzling features difficult to overcome.

15 A further object of the invention is the provision of a game in which the principles of base-ball are involved and which consists essentially of a diamond having the position of the players properly located 20 thereon and determined by holes which receive the object or playing ball.

Further objects of the invention will appear as the following specific description is read in connection with the accompanying 25 drawing which forms a part of this application, and in which:—

Figure 1 is a plan view. Fig. 2 is a transverse sectional view taken on the line 2—2 of Fig. 1. Fig. 3 is a horizontal sectional 30 view taken midway between the top and bottom of the case or box. Fig. 4 is a transverse sectional view taken on line 4—4 of Fig. 1.

Referring more particularly to the drawing, 1 represents a box having sides 1, ends 2 and 3, a base-board 4 and a glass cover or top 5. The base board has positioned thereon and extending diagonally from the sides to the end 2 a pair of guiding strips 6 which 40 converge to a receiving pocket 7, the purpose of which will be hereinafter described.

Located between the base board 4 and glass top 5 is a playing board 8 separated a sufficient distance from the top and base-board to permit of the convenient rolling of the playing object not shown which preferably consists of a heavy ball of any suitable material. The playing board 8 is laid out in the manner of a base ball field and is preferably constructed of papier mâché or similar substance having placed therein a plurality of grooves 10 and other grooves 11 representing the base lines. The bases are indicated at 12, 13, 14 and 15, the latter 55 being the home plate and the others, the first, second and third bases, in the order

named. At each of the first, second and third bases, the board is provided with a recess or offset pocket 16 in which the ball 9 may lodge and adjacent these pockets 60 the board is apertured as shown at 17 to provide openings for the passage of the ball to the base-board 4, where, upon tilting of the apertures, the ball will be guided by the strip 6 to the pocket 7 where it may be removed through an opening 18 in the playing board 8. There are other openings 19 provided throughout the infield which the balls are adapted to pass through so as to represent "outs" by possible flies and short 70 foul. The outfield players represented by the holes 20 are connected to the base-lines by grooves 21 and 22. The other openings may be arranged around the board beyond the lines indicated, if desired, but it is believed that the present number will present a sufficiently difficult problem without additional hazards. It will be noticed that the pitcher's position, which is also represented by an aperture, is lower than the 80 other points, and that the board is inclined in all directions from the center or that the ball has a natural tendency to travel toward the pitcher's position, thereby making it more difficult for the ball to travel the base-lines than would be the case where the playing board were level.

In playing the game, the operator starts the game from the home plate and it is his object to get the ball in the sockets or 90 pockets 16 and out of them along the base lines from first to second, second to third and back to home without passing through any of the openings. If the ball which represents the player falls through any of the 95 openings represented at 17, the player is considered to be put out by one of the basemen. If it enters the opening at the short-stop's position, the player is considered to be put out by either of these players. Difficulty of the game resides in getting the ball 100 out of the safe pockets 16 and causing it to travel a continuous path around the base lines.

What is claimed is:—

1. A base ball game apparatus comprising an elongated box-like structure, including a bottom, glass top, side and end walls, a playing board interposed between said top and bottom and spaced from both, said 110 board having a diamond shaped pathway indicative of a ball field, said board having

an opening at the juncture of the adjacent pathways and also a pocket at one side of each opening, said pocket extending beyond the outline of the pathway, the surface of said board bounded by said pathway defining the infield and having a plurality of irregularly disposed grooves leading from different points on said surface to the different pathways and communicating therewith, and a playing object adapted to travel over said board.

2. A base ball game apparatus comprising an elongated box-like structure, including a bottom, glass top, side and end walls, a playing board interposed between said top and bottom and spaced from both, said playing board having a diamond shaped pathway indicative of a ball field, and an opening at the juncture of the adjacent sides of the pathway, and also a pocket at one side of each opening, said pocket extending beyond the outline of the pathway, the surface bounded by said pathway defining the

infield and having a plurality of irregularly disposed grooves leading from different points on said surface to the different sides of the pathway and communicating with the latter, said board having a plurality of openings beyond said pathway indicative of certain players' positions, two sides of the said pathway leading to a pocket adjacent one end of the board indicative of the home plate, a playing object adapted to travel over the board, and a pair of convergently disposed members arranged between the board and said bottom for guiding the playing object toward said home plate subsequent to the passing of the object through any of said openings.

In testimony whereof I affix my signature in presence of two witnesses.

WILLIAM A. MELIUS.
